(57) **CLAIM**

The ornamental design for a water tank for indoor plant cultivator as shown and described.

DESCRIPTION

FIG. 1 is a front perspective view of the water tank for indoor plant cultivator showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a cross-sectional perspective view taken along line 8-8 in FIG. 6;

FIG. 9 is the view of FIG. 8 in an alternate configuration of use;

FIG. 10 is a perspective view of the water tank for indoor plant cultivator with environmental structure removed for clarity of illustration of the claimed design; and,

FIG. 11 is a perspective view showing the water tank for indoor plant cultivator with additional environmental structure.

The broken lines depict portions of the water tank for indoor plant cultivator that form no part of the claimed design. The broken line showing of an indoor plant cultivator with handle in FIG. 11 is for the purpose of illustrating environmental structure and forms no part of the claimed design.

1 Claim, 11 Drawing Sheets
